UNITED STATES PATENT OFFICE.

JOHN E. OSTLINE, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SERVICE OBSERVING EQUIPMENT FOR TELEPHONE SYSTEMS.

Application filed November 20, 1922, Serial No. 601,951. Renewed November 12, 1926.

The present invention relates in general to traffic observation equipment for use in observing the quality of service furnished in a telephone system, but is more particularly concerned with equipment of this type for use in multi-office automatic telephone systems; and the general object of the invention is to provide new and improved circuit arrangements and apparatus by means of which an operator at a centralized office can observe, monitor, or supervise the service on groups of trunk lines or lines located at a plurality of outlying offices or exchanges.

A special feature of the invention is the provision of means whereby trunks from any office in a multi-office telephone system may be automatically cut in to a centralized operator's position for observation purposes, together with the provision of means for preventing two such trunks being cut in at the same time.

Another feature is an arrangement whereby the numbers of the trunks of the outlying or observed offices are indicated by indicating lamps part of which are common to all observed trunks, resulting in the saving of considerable lamp equipment.

A further feature of the invention is the provision of means whereby two operators may observe traffic at the centralized office, and the provision of means for alternately distributing the trunks cut in to the two operators.

Still another feature is the provision of auxiliary observing equipment which may be readily connected at any of the offices to be observed, and which, upon such connection, automatically disconnects that office from the centralized equipment.

There are other objects of the invention which have not been mentioned, but which, together with the foregoing, will be described in the detailed description which is to follow.

Referring now to the drawings, comprising Figs. 1 to 6, inclusive, Figs. 2, 3, 4, and 5 should be placed in order with the corresponding lines at the ends thereof in alinement, and Fig. 1 should be placed above Fig. 2 with the corresponding inter-connecting lines in alinement. When laid out in the above manner the drawings show the complete circuits of a traffic observing system embodying the invention. Fig. 1 shows cer-

tain automatic equipment of the type usually used by a calling subscriber in extending an ordinary telephone connection. Figs. 2 and 3 taken together represent equipment which is located at an exchange to be observed, and is used for associating trunks to be observed with the central observing operator, for indicating at the observed office the number of the trunk cut in, and for controlling associated equipment for causing such trunk indication to also take place at the centralized office. Figs. 4 and 5 taken together comprise equipment located at the observing exchange, which is adapted to work in conjunction with a plurality of observed exchanges each having equipment such as shown in Figs. 2 and 3. Fig. 6 shows an operator's observing equipment which is adapted for use in conjunction with equipment such as shown in Figs. 2 and 3, when it is desired to concentrate the observation on the trunks of a particular exchange.

Now referring particularly to Fig. 1, the sub-station A is of the usual type, having talking, signalling, and switch controlling instrumentalities. The line switch C is of the well known rotary type in which the wipers have no normal position and move in a forward direction only. The line relay 112 is slow to pull up and release, as indicated by the solid black upper portion; while the relays throughout the drawings, having their lower portions shaded, are slow to release only. The selector D is mechanically of the usual vertical and rotary type, and accordingly its bank contacts are arranged in horizontal rows or levels. The terminal block TB is located at a point in the observed office where it is found most convenient to extend jumpers to trunks or lines to be observed. These jumpers may be fixed to the terminals of the terminal block, and may be provided with clips or the like to permit their being readily switched from one group of trunks or lines to another as desired. One jumper is shown in the drawing as comprising conductors 102, 103, and 104, and connects the trunk line extending to selector D with the first set of terminals on the terminal block TB.

Referring to Fig. 2, this shows in heavy lines the talking conductors 236 and 237 of an observation trunk, which extends through Fig. 3 to the central observing equipment.

Figs. 4 and 5. This observation trunk is common to all connecting trunks in the same office. As shown in the drawings it has been assumed that 50 is the maximum number of trunks which have access to the observing trunk. There will therefore be 50 connecting trunks (such as the trunk comprising conductors 107, 108, and 109) permanently connected to sets of terminals on the terminal block TB (Fig. 1). Each such trunk has two relays such as 201 and 211 individual to it. One of these relays is for connecting its associated trunk to the talking conductors 236 and 237, and for operating a unit trunk indicating lamp, and the other relay is for preventing such connection being made when the observation trunk is already in use, when trunks are not being observed, or when the observing equipment has been made ready to observe trunks at a time when trunks are already in use.

These 50 connecting trunks with their corresponding relay sets are divided into five groups of ten each. Each group is provided with one relay such as 245, and with another relay 251. In the drawing only one of the five relays 245 is shown; however, those not shown are operated over the same common conductor over which 245 is operated. These relays each carry ten pairs of control springs, one pair for each trunk in the group, and operate as a unit to control means at their associated exchange for preparing the equipment to permit trunks to be cut in. One common relay could be used for this purpose instead of five, but such a relay would be required to carry 50 sets of contact springs, which is not thought to be desirable.

The group relays 251 to 255, inclusive, are each provided with an operating circuit individual to the group to which they belong. These relays function to operate an associated group trunk indicating lamp, to operate an impulse sender switch controlling relay, and in addition aid in bringing about the operation of a trunk cut in signal at the observing office.

The relay 242 is common to the observed exchange and is provided to complete the operating circuit of the relays such as 245. This relay 242 has its original operating circuit extending through series contacts of all cut in relays of each group in the exchange. If this circuit happens to be open the relay 242 acts as an alarm relay, controlling the buzzer B (Fig. 3) at the observed office.

Relays 270, 275, 280, 296 and 257 are common to the observed exchange and function to take care of various details which will be pointed out in the detailed description which is to follow. The induction coil I is adapted to be associated with the observation trunk talking conductors 236 and 237 when the attendant is being signalled by an observing operator, and acts to inform the operator

that the signal is operating. All of these operations will be described in detail subsequently.

Now referring to Fig. 3, it will be seen that the observing trunk conductors 236 and 237 terminate in the left hand windings of the repeating coil R. From the right hand windings of the repeating coil the observing trunk talking conductors are first indicated by reference numerals 366 and 318, and then by numerals 415 and 368. These latter conductors extend to the observing office together with the combination lock and trunk indicating impulse, and impulse conductors 350 and 352 respectively.

The buzzer B is provided for signalling an attendant and may be operated either when the relay 242 (Fig. 2) fails to operate, or may be operated by the observing operator when the attendant is desired. The key K⁵ is for use by the attendant to restart the operation of the buzzer for a purpose which will be later pointed out.

The polar relay 376 is bridged across the observing trunk conductors 236 and 237, and is adapted to respond to each interruption of a subscriber's calling device, to send ground impulses over the impulse conductors 379 and 352 to operate a pen register at the observing office, the relay 371 at the same time being also maintained energized to hold open the primary winding of the repeating coil R, to prevent excessive clicks from being produced in the observing operator's receiver (Fig. 5).

The switch SS is of the same mechanical construction as the line switch C of Fig. 1. This switch with its associated relays 305, 311 and 325 operates when a trunk has been cut in, to transmit series of impulses over the combination locking and impulse trunk conductor 350 to set up trunk lamp selecting switches at the observing office. The impulse series sent out by this switch are determined by the particular bank contacts which are grounded when a trunk number is displayed on the group and units lamps.

The equipment described up to this point is all located in one office. However, there may be any number of offices in the system, each office having equipment identical to that shown and described. In the present case it has been assumed that there are ten observed offices. It has further been assumed that the office having the equipment shown in Figs. 2 and 3 is the No. 1 office. The observation trunk comprising the talking, combination locking and impulsing, and the impulsing conductors 415, 368, 350, and 352 is individual to the No. 1 office and is one of ten such trunks terminating in suitable equipment at the observing office.

Now referring to Fig. 4, it will be seen that the observation trunk above mentioned terminates in springs of office cut in relay

401. The relay 401 is individual to the No. 1 exchange. In the present case it having been assumed that there are ten offices in the system there will be ten such relays, only two of which are shown. The relay 410 is assumed to be the tenth such relay, and is therefore individual to the tenth or last trunk as indicated. The relay 405 is common to all observed offices, and when operated causes the observing equipment at each office in the system to permit trunks to be cut in, and also prepares an operating circuit for all office relays such as 401 and 410. When a trunk is cut in to the observing trunk of any office, the corresponding relay such as 401 will pull up to make inoperative all other office relays, and to at the same time extend the observed trunk through to the observation operator's equipment.

401', 410' and 405' at the lower portion of the drawing, and their associated circuits, are identical to those just described. These relays have no function as long as only one observing operator is required. However, in anticipation of future requirements a jumper block is provided, and upon original installation if only one observing position is required the solid line jumpers shown on the jumper block are all that are required. If at a future date it is desired to provide a second position, it is only necessary to connect the circuits of relays 401', 410' and 405' to the lower terminals of the jumper block JB, and to substitute the jumpers indicated by dotted lines for those indicated as solid lines. The conductors Y will of course extend to the No. 2 observation set which will be identical to the equipment shown in Fig. 5. When the two positions are in service the relays 405 and 405' operate alternately to distribute the calls to the two positions.

401. Referring now to Fig. 5 it will be seen that the talking circuit extends via talking conductors 506 and 507 of the observation trunk to the left hand windings of the repeating coil R', and continues from the right hand windings of the same through talking key K³. The key K³ is provided to enable the operator to switch from the high efficiency monitoring circuit to a standard operator's talking circuit, so that the operator may converse with the calling subscriber or an attendant when there is trouble. The remaining keys K', K² and K are for locking up the connection, signalling an attendant and releasing the connection respectively. The lamps 1 and 10 shown under the heading "Office", represent the first and tenth office. Since there are 10 offices in the system there will be 10 office lamps, for indicating offices one to ten. The lamp 514 is a trunk cut in lamp, for indicating to the observer that a trunk is cut in to her set. The lamp 513 is provided to give the observing operator hook-

switch supervision on the calling line. The pen register PR is operated over the conductor 437 in response to impulses sent to it by the previously mentioned polarized relay 376, (Fig. 3) and records on a tape the called number dialled by the subscriber.

70 The trunk lamp selecting switches T' and T² are of simple and well known construction, having operating magnets 515 and 532 which by means of an ordinary pawl and ratchet (not shown) move their wipers over their respective sets of bank contacts. The release magnets 530 and 534 are provided for the purpose of restoring the wiper sets to normal. The impulse series for operating 75 these two switches are transmitted to the impulsing relay 520 by the switch SS (Fig. 3). With the aid of relays 521 and 517 the switch T' is controlled to position one of its wipers so as to engage a group lamp corresponding to the group lamp which is glowing at the observed exchange. At the termination of the first series of impulses the relays 521 and 517 bring about the switching 80 of the impulse circuit to the controlling magnet of the switch T², and responsive to the second series of impulses sent out by switch SS, one of the wipers of the switch T² is positioned on a contact connected to a unit lamp corresponding to the unit lamp which is glowing in the observed office. These lamps therefore are caused to glow, to inform the observing operator the number of the trunk in use at the observed exchange.

90 The equipment shown in Fig. 6 is the same as corresponding equipment shown in Fig. 5 and operates the same so far as the operator is concerned. This equipment is for use when it is desired to concentrate observation upon a particular one of the exchanges, and is provided with a jack J² which may be inserted in a jack J³ (Fig. 3) of any such exchange. An observing operator in using this equipment does not need the office or trunk indicating equipment shown in Fig. 5, but uses the trunk indicating equipment at the observed office.

100 Having briefly described the mechanical structure of the various switches shown in the drawings, and having described the relation of the various parts to the system as a whole, a detailed explanation will now be given.

105 The operations which take place when trunks become busy during the time the observing equipment is idle (at normal) will first be pointed out, after which the various operations which take place when the observing operator prepares the equipment for receiving calls will be described.

110 When the observing circuits are not in use the relay 245 (Fig. 2) is deenergized, and likewise all other such relays (not shown) of the remaining groups and of all other 115

offices. When a call is initiated, for instance over the connecting trunk having conductors 107, 108 and 109, the private conductor 109 will be grounded. This will result in the operation of relay 201. This circuit may be traced from grounded conductor 109, lower winding of relay 201, springs controlled by armature 221 and the lower winding of relay 211 to battery. The pull up winding of relay 211 is of very low resistance as compared with that of relay 201 and therefore relay 211 is not actuated at this time. The relay 201 locks up over its armature 221 and its working contact, and through its upper winding to battery. If the observation equipment is in the meantime placed in readiness to observe calls, all the relays 245 of the observed exchanges will be energized. The energization of these 20 relays causes the lower windings of all relays 201 to be short circuited. This does not, however, cause the deenergization of any relay 201, this relay remaining locked up through its upper winding, but acts to 25 prevent any such relay which is not energized from energizing until a connecting trunk has been connected to the observation trunk. It will be seen therefore that the relay 201 or any other like relays which are 30 operated will remain operated until their associated trunk becomes idle. This prevents these prior calls from interfering with calls initiated after the circuit is placed in 35 readiness for observation.

Now referring to Fig. 5, when the operator is ready to begin work, she prepares the equipment for observation by inserting the receiver plug P into the jack J, which causes the operation of relay 405 (Fig. 4). This 40 relay in turn operates to complete an operating circuit for each relay 226, (Fig. 2) there being one such relay in each observed office, and in addition, prepares a circuit for all relays such as 401 and 410, there being 45 one such relay at the observing office individual to each observed office. Now considering only the observed office shown in Figs. 1, 2 and 3, the other offices being the same, the operation is as follows:

The operator upon inserting the jack J into plug P completes a circuit for relay 405, as previously stated. This circuit may be traced from grounded springs of jack J, conductor 502, through springs of release key K, conductor 503, springs controlled by armature 403 of relay 401, (Fig. 4) springs controlled by armature 404 of relay 410, through jumper 424 on the jumper block JB, and the winding of relay 405 to battery. Relay 405 55 operates and at its armature 407 prepares a circuit for the pull up windings of all office cut in relays such as 401 and 410. Two of the ten such circuits are shown, and may be traced from battery, resistance 406, working contact of armature 407 and the said armature 408, to terminal 429 of the jumper block JB where the circuit divides, one branch extending by way of jumper 431 to the upper winding of relay 401, and the other branch extending by way of jumper 427 of the jumper block to the upper winding of relay 410. Relay 405 also closes an operating circuit for the common grounding relay 226. This circuit may be traced from the working contact of armature 411 and the said armature, conductor 412, to terminal 428 of the jumper block JB, by way of jumper 430 to terminal 419, where the circuit divides into as many branches as there are observed exchanges, the branch shown complete extending by way of jumper 413, springs controlled by armature 414, conductor 415, armature 316 and its resting contact, (Fig. 3) conductor 318, upper right hand winding of the repeating coil R, conductor 319, resting contact of armature 320 and the said armature, conductor 322, resting contact of armature 323 and the said armature, conductor 324, through springs controlled by armature 225, and the winding of relay 226 to battery. Relay 226 energizes over this circuit, and locks up over a circuit independent of armature 323 of relay 325 (Fig. 3). This circuit may be traced from the grounded conductor 322 to armature 225 and its working contact, and the winding of relay 226 to battery. Relay 226 in operating causes ground to be applied to the common conductor 228. This circuit may be traced from grounded working contact of armature 227 and the said armature, and conductor 228, and also completes a circuit for the relay 242 extending from the grounded conductor 228, conductor 229, springs controlled by armature 230, conductor 239 (which includes eight sets of springs similar to those controlled by armature 230), springs controlled by armature 240, conductor 241, through ten similar sets of springs in each group (not shown), through the winding of relay 242 to battery. Relay 242 operates and completes a circuit for relay 245, extending from the common grounded conductor 228, armature 243 and its working contact, conductor 244, and the winding of relay 245 to battery. Relay 245 and all other such relays associated with groups 2 to 5 (not shown) energize and short circuit the lower winding of all relays such as 201 and 210 in each group. The observation equipment is now in readiness to observe calls.

Had the relay 242 failed to operate, (due to a pair of springs such as those controlled by armature 230 being open) the attendant or switchboard man at the observed exchange would have been signalled by the buzzer B (Fig. 3). This signalling circuit may be traced from the grounded conductor 228, armature 243 and its resting contact, conductor 246, armature 247 and its resting contact,

tact, induction coil winding 248, conductor 349, and the buzzer B to battery. The attendant upon hearing the buzzer and noting that the trunk lamps are not glowing knows 5 that a series contact is open; and that the same must be found and the trouble corrected before trunks in that office can be observed.

The observation set being in condition to 10 observe calls, it will now be assumed that a subscriber at substation A (Fig. 1) initiates a call. When the receiver is removed at sub-station A, a circuit is closed over the line conductors 110 and 111 for the line relay 112 15 of the line switch C. Upon the energization of the line relay 112, the line switch C operates in the usual manner to select an idle trunk, which trunk, it will be assumed, is the one extending to the selector D. As soon 20 as this trunk is found, the switching relay 113 energizes at the end of the trunk selecting movement, or immediately upon the energization of line relay 112 in case the line switch was already standing upon an idle 25 trunk, and extends the calling line through to the selector D. The line and release relays 105 and 106 of the selector D now energize in the usual manner, and the latter upon energization places ground upon the release 30 trunk conductor 104 so as to establish the usual holding circuit for the line switch C. As is well known, ground is maintained on the conductor 104 throughout the connection, and this is all that need be considered at this 35 time. A circuit may now be traced from the grounded conductor 104 to the terminal block TB, conductor 109, working contact of armature 270 and the said armature, springs controlled by armature 221, and the lower 40 winding of relay 211 to battery. The relay 211 operates and locks itself over a circuit extending from the grounded conductor 228, conductor 229, working contact of armature 230 and the said armature, and the upper 45 winding of relay 211 to battery. This operation also removes ground from the portion of the loop circuit extending to relay 242. If it should so happen that more than one call was initiated at the same time, only 50 the relay nearest the common ground would lock up, and it would cut off the locking ground from all other such relays. Armature 231 of relay 211 in operating applies ground to the units lamp O by way of the conductor 232, causing the units lamp O 55 to glow. At armatures 234 and 235, the trunk conductors 107 and 108 are connected to the trunk conductors 236 and 237 across which is bridged the left hand, or primary winding of the repeating coil R. It will be recalled that the operation of the armature 230 disconnected ground from the loop conductor 239, which formerly maintained the relay 242 energized. Relay 242 now restores 60 breaking the previously traced operating cir-

cuit for the relay 245, and at the same time closes the previously traced circuit for the buzzer B, which is ineffective at this time as this circuit is opened a moment later by relay 257. Relay 245 restores to normal, removing the shunt from around the lower winding of all relays such as 201 and 210. Relay 201 now operates over a circuit extending from the grounded conductor 109, lower winding of relay 201, springs controlled by 70 armature 221, and the lower winding of relay 211 to battery. Relay 201 in operating completes an operating circuit for group relay 251, and sender switch starting relay 257. This circuit may be traced from the grounded 75 working contact of armature 222 and the said armature, conductor 233, working contact of armature 223 and the said armature, conductor 250, springs controlled by armature 224, winding of relay 251, conductor 256, and the winding of relay 257 to battery. Relays 251 and 257 both operate. Relay 251 in operating completes a holding circuit for itself, and relay 257. This circuit extends 80 from the grounded conductor 228, conductor 229, armature 224 and its working contact, and the windings of relays 251 and 257 in series to battery. Another circuit is completed from grounded conductor 228, working contact of armature 260 of relay 251 and 85 the said armature, and conductor 261 extending to the group lamp O and to battery, causing this lamp to glow. This lamp, in conjunction with the unit lamp controlled by the relay 211, indicates to an attendant at the 90 observed office the number of trunk cut into the observation set. Relay 257 in operating, at its armature 247 breaks the previously described buzzer circuit, and at its armature 258 grounds conductor 259. 95

It may be well to note at this time that should the trunk made busy have been extended over the connecting trunk conductors 107', 108', and 109', resulting in the operation of relay 220, that the locking circuit 100 for such relay would have extended over the conductor 239, through the various series contacts of all other relays such as the contacts controlled by armature 230 of relay 211, of the entire No. 0 group to the conductor 110 229, and to the common conductor 228 to ground, in which case it will be noted that the circuit would extend through nine pairs of break contacts. It will be seen that if no 115 special provision were made, should the tenth trunk of the fifth group become busy, the locking circuit for the relays, such as 211 or 220, would extend through 49 sets of contacts before reaching the common grounded conductor 228. In the present case, this undesirable series holding circuit has been much 120 improved by providing a shunt around all the groups of series contacts ahead of the particular group in which a trunk is cut in. This is accomplished by providing each 125 130

group relay, with the exception of the first, with an armature such as 263, which, when operated connects the common ground conductor 228 direct to the series springs controlled by the first trunk relay of its respective group.

Returning to the operation of the group relay 251, this relay at its armature 262 completes a circuit for office cut in relay 401 (Fig. 4). This circuit may be traced from the grounded conductor 250, working contact of armature 262 and the said armature, conductor 264, armature 364 and its resting contact, resistance 365, lower right hand winding of repeating coil R, conductor 366, resting contact of armature 367 and the said armature, conductor 368, armature 468 and its resting contact, to the upper winding of relay 401 over the previously traced circuit to battery. Relay 401 operates and locks itself over a circuit extending from the grounded contact 501 of the operator's jack, conductor 502, through springs of the release key K, conductor 503, working contact of armature 403 and the said armature, and the lower winding of relay 401 to battery. Relay 401 at its armature 403 also removes ground from the series holding circuit of relay 405, breaking the previously prepared locking circuit for all other office cut in relays such as 401, 410. If two observing trunks attempt to cut in the central observing trunk at the same time, only the relay 401 nearest the grounded conductor 503 will lock up, and it in so doing will break the initial operating circuit of all other office cut in relays. The relay 405 in restoring to normal disconnects ground from all conductors such as 415 leading to the different common grounding relays such as 226 (Fig. 2). This does not, however, cause the deenergization of the relay 226 in the exchange in which a call has been cut in for reasons which will be pointed out subsequently. The relay 405 also removes battery from the pull up winding of all office cut in relays, thereby making it impossible for a second office to be cut in. The operation of armature 450 of relay 401 causes the office indicating lamp to glow, informing the operator the office in which observation is being made; armature 416 connects the impulse conductor 352 through to the pen register PR (Fig. 5); armature 417 connects the combination lock and indicating impulse conductor 350 to the impulsing relay 520 (Fig. 5); armatures 414 and 468 connect the office observing trunk to the central observing trunk extending by way of talking conductors 506 and 507, repeating coils R' and R² and through contacts of the talking key K³ to the observer's head set, permitting the operator to listen in during the progress of the call.

Referring to relay 226 (Fig. 2), it will be recalled that this relay was originally ener-

gized over the upper heavy talking conductor 415 (Fig. 3). When the office cut in relay 401 (Fig. 4) is energized the ground formerly supplied to the above conductor by the relay 405, is cut off by the operation of armature 414 and a new holding ground substituted, which extends through the winding of trunk cut in relay 504 (Fig. 5). This new circuit may be traced from conductor 415, working contact of armature 414 and the said armature, talking conductor 506, upper left hand winding of the repeating coil R', conductor 505 and the winding of relay 504 to the grounded conductor 503. The closure of the above described circuit in addition to holding energized the relay 226, belonging to the office under observation, causes the operation of the trunk cut in relay, which in operating causes the trunk cut in lamp 514 to glow. This acts as a guard to show the observer that a trunk is cut in to the observation set, even if the office lamp fails to glow, indicating that calls cannot be received from other offices or trunks, until the release key is operated.

The operation of the office cut in relay 401 also completed an operating circuit for the supervisory relay 536. This circuit extends from the working contact of armature 222 of relay 201 and the said armature, conductor 233, working contact of armature 223 and the said armature, conductor 250, working contact of armature 262 and the said armature, conductor 264, resting contact of armature 364 of relay 300 (Fig. 3) and the said armature, resistance 365, lower right hand winding of repeating coil R, talking conductor 366, resting contact of armature 367 and the said armature, talking conductor 368, armature 468 and its working contact, conductor 507, lower left hand winding of repeating coil R' and the winding of the supervisory relay 536 to battery. This relay operates, causing the subscriber's pilot lamp 513 to glow. Since the ground for operating relay 536 is supplied by the relay 201 (Fig. 2) it will be seen that the moment the calling subscriber hangs up his receiver the relays 201 and 536 will deenergize causing the subscriber's pilot lamp to be extinguished.

In addition to various results accomplished by the operation of relay 401, the observer is automatically "listened in" on the trunk over which the call is made. This listening circuit may be traced as follows: From the observed trunk conductors 107, and 108 armatures 234, and 235 and their working contacts, conductors 236, and 237, to the left hand windings of the repeating coil R. From the right hand or secondary windings of repeating coil R, conductors 318 and 366, the resting contacts of armatures 316 and 367 and the said armatures, and conductors 415 and 368 to the left hand windings of

repeating coil R' . From the right hand windings of repeating coil R' to the left hand winding of repeating coil R^2 . From the right hand winding of repeating coil R^2 , through contacts of the talking key K^3 to the operator's receiver.

The various operations which have been described when an initiated call is cut in to the observer, all take place in close sequence when the calling party removes the receiver from the switch-hook. Immediately thereafter, the trunk indication takes place, and usually within a few seconds the dialing of the desired number by the subscriber takes place. From this point, the observer will in the majority of cases first listen for the overflow, ringing, or busy tone; the answer of the called party; record the number dialed as indicated on the pen register tape; record the office and the number of the trunk observed therein, and make any other records as required by routine. After ascertaining that the calling party has secured the party desired, and that the connection is satisfactory, the observer will place the equipment in readiness for the next call by operating the release key K . In cases where trouble or any non-standard condition is encountered, the locking, talking, signalling and tracer tone features will be brought into action. These various features as well as others previously mentioned will now be described.

Trunk indicating.

This feature is provided to enable the observer at the centralized observation point to know on which trunk the observation is being made. As in the previous description, the trunks are indicated in the observed office by group and unit lamps. When a call is cut in the relay 257 is operated over a circuit previously described, completing an initial operating circuit for the motor magnet 303 of the sending switch SS . This circuit may be traced from the grounded working contact of armature 258 and the said armature, conductor 259, through springs controlled by armature 301, resting contact of armature 302 and the said armature, and the winding of magnet 303 to battery. The magnet 303 operates and at its armature 304, removes a normal shunt from the winding of relay 305, which relay now energizes. The relay 305 operates and at its armature 302 breaks the operating circuit of magnet 303, magnet 303 in restoring its armatures replaces the shunt about the relay 305, and steps its wipers 306, 307, and 308, one step. A circuit may now be traced from the grounded wiper 308 and the upper winding of relay 325 to battery. Relay 325 operates and at its armature 301 substitutes ground from the wiper 308 for the grounded conductor 259 and keeps the rotary magnet

303 operating, at a speed determined by the operation of relay 305. Relay 325 also locks itself up over its lower winding, by way of armature 309 and its working contact to the starting ground on conductor 259. It will be seen that the motor magnet 303 and the relay 305 will operate alternately until the wiper 308 steps off the last grounded bank contact. At armature 323 of relay 325 the initial energizing circuit of the relay 226 is broken, so that should this relay become deenergized by the operator operating her release key, this relay cannot again become energized while the switch SS is off normal. It will be seen that if this means were not provided and another trunk was cut in to the observing equipment before the switch SS was restored to normal, an incorrect trunk indication would result. In the present case it has been assumed that the trunk cut in was the first trunk of the first group of the No. 1 observed exchange; therefore, as soon as the wiper 307 of the switch SS engages its sixth bank contact, which has been previously grounded by the group relay 251, a circuit may be traced from such grounded contact, the wiper 307, springs controlled by armature 310, the winding of relay 311, and resistance 312 to battery. Relay 311 operates over this circuit and locks itself to ground, by way of the working contact of armature 310 and the said armature, working contact of armature 301 and the said armature, to the grounded wiper 308. The operation of armature 313 prepares an impulse circuit which extends from the working contact of armature 304 to the working contact of armature 313 and the said armature, conductor 314, resting contact of armature 315 and the said armature, conductor 350, armature 417 and its working contact, conductor 418, through springs of the locking key K' , conductor 519, and the winding of impulsing relay 520 to battery. As soon as the magnet 303 again becomes energized, a ground impulse is transmitted from its grounded armature 304 and its working contact, over the above traced circuit, resulting in a momentary energization of the impulsing relay 520. This causes the operation of slow acting relay 521, and when the relay 520 deenergizes an impulse is repeated over a circuit extending from the grounded armature 522 and its resting contact, armature 523 and its working contact, armature 524 and its resting contact, and the winding of magnet 515 to battery, causing the wipers 527 and 536 of switch T' to be moved one step. After a short pause, the relay 521 will deenergize, and, in so doing, complete a circuit from grounded wiper 527 and its associated bank contact, armature 516 and its resting contact, springs controlled by armature 529 and the upper winding of relay 517 to battery. Relay 517

operates and at its armature 524, switches the impulsing circuit from magnet 515 of the switch T' into connection with the magnet 532 of the switch T². The relay 517 in operating also locks itself up at its armature 529, independent of the armature 516 of the relay 521.

Returning to the operation of the switch SS it will be recalled that the wipers 306, 10 307 and 308 were standing on their sixth bank contacts when the magnet 303 energized to send out the first impulse. When the magnet 303 deenergizes the wipers 306, 307, and 308, are stepped to their seventh 15 bank contacts. A circuit may now be traced from the grounded bank contact 335, wiper 306, through resistance 312 to battery. This shunts battery from relay 311, causing the same to deenergize. The relay 311 restores 20 to normal, and armature 313 disconnects the impulse conductor 314 from control of magnet 303. The next two steps taken by the switch SS are provided to allow ample time for the slow release relay 521 to de- 25 energize after the first impulse or series of impulses has been transmitted to the relay 520. As soon as wiper 307 comes into engagement with its bank contact which is associated with the units lamp O, relay 311 is 30 again operated. The following energization of magnet 303 now results in the transmission of an impulse over the previously traced path to the relay 520. The relay 520 is again operated, resulting in the operation of relay 35 521. The relay 520 now causes one impulse to be transmitted from the grounded armature 522 and its resting contact, armature 523 and its working contact, armature 524 and its working contact, and the winding of 40 magnet 532 to battery. This causes the switch T² to step its wipers 533 and 534 one step. As soon as the relay 521 falls back, a circuit for the indicating lamp O (Fig. 5), of the group and O of the units lamp set 45 will glow, thereby indicating to the observer the number of the trunk under observation.

If the trunk under observation had been the tenth trunk in the fifth group, the second and tenth bank contacts traversed by 50 wiper 307 would have been grounded. Assuming this to be the case, as soon as wiper 307 reaches its second bank contact, the relay 311 is locked up, which permits the magnet 303 to transmit five impulses to the relay 520, causing the switch T' to step its wipers to the fifth bank contact. After the fifth impulse, the deenergization of magnet 303 causes wiper 306 to again engage its ground- 55 ed contact 335. The relay 311, therefore, 60 deenergizes to disconnect the impulse conductor. The next two idle steps allow sufficient time to permit the relay 521 to deenergize and to allow the switching over operation to be effected. When the wiper 307 65 engages its tenth contact, the relay 311 is

again energized, and it will be quite obvious that ten more impulses are now transmitted to the relay 520 before the relay 311 can be again deenergized. This results in the switch T² having its wipers set on their tenth 70 bank contacts. When the relay 521 deenergizes the group lamp 4 and the unit lamp 9 will glow, indicating that trunk 49 is the trunk under observation.

75

Dialing and number recording.

Referring now to Fig. 3, it will be recalled that the left hand winding of the repeating coil R was connected in bridge of the observed trunk by the operation of the relay 211, by way of the conductors 236 and 237. A polarized relay 376 is included in the bridge. This relay is of very high resistance, and will not in any manner effect the operation of the line, or impulsing relay 105 85 of the selector D. When a calling subscriber operates his calling device to transmit the various series of impulses corresponding to the called number of the desired subscriber, the short circuit produced 90 by the talking equipment at the sub-station A is removed each time the calling device springs are operated, and the polarized relay 376 responds to the dial impulses, without interfering with the call in any way. It will 95 be noted that the armature 378 of the relay 376 is grounded by the conductor 264, which conductor may be grounded by any group relay, and is at this time grounded by the group relay 251. It follows that each time 100 the armature 378 is attracted, a ground impulse is transmitted to the pen register PR over a path extending from the conductor 379, resting contact of armature 380 and the said armature, conductor 352, armature 416 105 and its working contact, conductor 437, and the pen register PR to battery. It will therefore be seen that the pen register PR will record any number dialed by the calling subscriber. Another branch of the impulsing circuit just traced extends from conductor 379 to the winding of slow relay 371 to battery. This relay remains energized during each series of impulses, and opens 110 at its armature 370 a point in the primary, 115 or left hand windings of the repeating coil R. This is done to prevent unbearably loud clicks being reproduced into the receiver of the observing operator; it does not, however, entirely prevent the clicks from being 120 heard, permitting the operator to actually hear the dialing taking place.

Locking.

If, on account of trouble or any non-standard condition, the observing operator desires to lock up the observed call, the locking key K' is operated. This results in the operation of the relay 280 at the observed exchange, over a circuit traced from the 130

grounded conductor 502, springs of the signal key K^2 , springs of the locking key K' , in operated position, conductor 418, working contact of armature 417 and the said armature, conductor 350, armature 315 and its resting contact, conductor 314, armature 313 and its resting contact, conductor 353, and the winding of relay 280 to battery. The relay 280 in operating completes a circuit from the grounded working contact of armature 227 and the said armature, armature 283 and its working contact, and the winding of relay 275 to battery. Relay 275 operates and at its armature 286 places a 1000 ohm non-inductive resistance 288, across the condenser 372 of the repeating coil R . This places a loop across the two sides of the observed trunk, which prevents the release of any complete or partially set up connection, but does not interfere with transmission. This feature is very desirable in certain instances where it is found necessary to lock up a call during conversation.

Talking.

Whenever the observer finds it necessary to talk to a subscriber or an attendant, the talking key K^3 will be operated. The operation of this key brings about the disconnection of the high efficiency monitoring circuit and substitutes therefor a standard operator's talking circuit comprising the repeater R^3 , the transmitter T , etc. The observing operator may now converse with either the calling subscriber or the attendant as the case may be.

Signalling.

When any non-standard condition exists where investigation is required by the observer, the call is first locked up in the manner previously described. The observing operator, after operating the talking key and conversing with the calling subscriber advising him to hang up and call a little later, will then signal the attendant at the distant exchange by operating the signalling key K^2 . When this key is operated, the previously traced circuit extending to the relay 280 is momentarily interrupted, resulting in the transmission of a ground impulse extending from the armature 283 and its resting contact to armature 284 and its working contact, and the lower winding of relay 270 to battery. This relay locks up in multiple with the resistance 290 in bridge of the extended trunk conductors 236 and 237 at its armature 289, and at its armature 291 completes a circuit which may be traced from the grounded armature 282 and its working contact, working contact of armature 291 and the said armature, the primary winding 248 of induction coil I , conductor 349, and the buzzer B to battery. This will cause the buzzer B to operate, to

signal the attendant. It should be observed that the secondary winding 293 of the induction coil I is connected in series with the resistance 290, and the winding of relay 270 which is placed across the extended trunk conductors 236 and 237, and therefore, when the buzzer is operated, a tone will be impressed upon the trunk, indicating to the observer that the attendant is being signalled. When the attendant responds by inserting the plug P' (Fig. 3) into the jack J' , he also depresses the key K^4 . The shunting effect of the attendant's talking set will cause the relay 270 to release, which in turn will stop the buzzer. Conversation may now take place, and action taken to correct the non-standard condition.

Tracer tone.

After the attendant has received the observer's report and ascertained the number of the trunk from the trunk indicating lamps, he will trace the connection to the point where it failed by examining in turn each of the switches involved in the connection. In order to assist him in doing this quickly and accurately, he places a tracer tone on the connection. This is the same tone as that used to indicate to the observer that the attendant's call signal is being operated. However, in this case, the attendant starts it by operating the non-locking button K^5 . This will again operate the relay 270 in an obvious manner, causing it to lock itself from the trunk battery and ground in the same manner as before. The attendant will now listen in on the various switches in the built up connection without cutting out the condenser in his set. This is done by inserting plug P' in the individual switch test jack (not shown) in the usual well known manner. When he reaches the point at which he wishes to lock up the connection, he grounds the holding trunk conductor to prevent the release of the switches. He also stops the tracer tone by again short circuiting the condenser in his set, and will at the same time advise the observing operator that the trouble is found, and that the trunk can now be released from the observation set.

Release.

When the observer desires to release the trunk connected to the set, the release key K is operated. The operation of the key K disconnects ground from the conductors 503 and 510, causing the release of relays 504, 401 and 226. Relay 504 at its grounded armature 518 removes ground from the cut in lamp 514, and applies ground to the release magnets 530 and 534 of the switches T^1 and T^2 . These magnets in turn operate and restore their respective wipers to nor-

mal. As soon as wipers 527 and 533 reach normal, the locking circuit for relay 517 is broken and this relay releases. Wiper 533 in restoring to normal also removes ground from the trunk indicating lamps. Relay 401 in restoring, at its armature 450 removes ground from conductor 451, causing the office lamp to be extinguished. Relay 226 upon restoring, removes ground from the common ground conductor 228. This results in the deenergization of the group relay 251 and trunk cut in relay 211. If the calling subscriber still has his receiver removed, the relay 201 will not restore at this time. The operator by permitting the non-locking release key K to restore to normal again completes a circuit for the operation of relay 226 identical to that previously described, thereby placing the circuit in readiness for the next call.

It should be noted that during the time a trunk is being observed that any trunks seized will operate only their individual relay such as 210, which will lock up from battery and its two windings in series to the grounded release trunk. The operation of this relay brings about the disconnection of its corresponding cut in relay; therefore, when the relay 226 again energizes the trunks already in use cannot be cut in, thereby insuring that only initiated calls will be cut in to the observer.

Where large multi-office exchanges are equipped with observation equipment such as has been described, it may be found desirable to provide equipment which permits two operators to take observation at the same time. This result has been attained by applicant, together with a novel method of distributing the trunks cut in equally between the two operators. Referring to Fig. 4, the relays 401', 410', and 405', and their associated circuits are identical to those shown in the upper half of the drawing, and the group of conductors Y correspond to the conductors 509, 503, 507, 506, 437, 418, and 451, and extend to equipment identical to that shown in Fig. 5. Now, when it is desired to change the equipment for use from one to two positions, the jumpers such as 413, 427, 430, and 431, are replaced by the jumpers indicated by the dotted lines.

Now, assuming that the two operators are about to observe trunks, and further assuming that the operator whose equipment is shown in Fig. 5 is the first to insert her plug P into the jack J, the relay 405 will operate in the manner previously described, and will, at its armature 421, open the operating circuit for the relay 405', which it will be seen can only become energized when the second operator inserts her receiver plug, and when relay 405 is deenergized. As soon as the trunk is cut in to the equipment, and the relay 405 is deenergized, the relay 405'

will then operate, and in so doing permit a second trunk to be cut in. The operation of relay 405' causes battery to be applied to the common conductor 423, by way of conductor 420 and jumper 422. From the common conductor 423 circuits extend through the pull up winding of each office relay 401', 410' to trunk conductors 368, 368', except the office relay corresponding to the trunk already in use. One such circuit may be traced from conductor 423 resting contact of armature 426 and the said armature, jumper 432, to the pull up winding of relay 410', through resting contact of armature 468' and the said armature, to the trunk conductor 368'. Assuming now that the trunk cut in to the No. 1 operator was extended from the No. 1 office, in which case the office relay 401 was operated, resulting in the disconnection of the pull up winding of the relay 401', which, like relay 401, is individual to the exchange which has a trunk cut in, it will be seen that the relay 401' has its pull up winding cut off at armature 425, to prevent battery from being applied through the winding of relay 401' to conductor 368 of the busy trunk. As soon as the No. 2 operator has a trunk cut in to her set, the relay 405' will be deenergized, and providing the No. 1 operator is ready to observe another trunk, the relay 405 will again become energized. It will be seen that the operation of relays 405 and 405' takes place alternately, thereby distributing the calls to the two operators as fast as the trunks are cut in.

Local observation.

In the circuit arrangements previously described, where observation is taken from a central point by one or two operators, there will be comparatively few trunks of a particular office observed in a given time. In certain instances, it may be desirable to concentrate observation on one exchange, so that the quality of service given by that particular exchange may be determined more accurately and in less time than would be otherwise possible. Referring now to Fig. 6, which comprises equipment identical to the corresponding equipment shown in Fig. 5. This equipment is adapted for use with equipment shown in Figs. 2 and 3, there being a jack J² provided which is adapted to be inserted in the jack J³ (Fig. 3). By inserting the jack J² into jack J³ the cut off relay 300 is operated, cutting off the trunk extending to the centralized observing equipment. The operation of this set is identical to that of the centralized set in so far as the observer is concerned, except that no office and trunk indicating lamps are provided. Since observation is being taken at the same office or exchange at which the trunks are located, the trunk indicating

lamps at that exchange may be used by the observer.

The circuit operation differs slightly from the centralized set in that the subscriber's 5 pilot lamp 518' is controlled directly over the conductor 264. The trunk cut in lamp 514' is operated in a similar manner, from common ground conductor 228, armature 243 and its resting contact, conductor 246, 10 armature 247 and its working contact, conductor 248 through the cut in lamp to battery.

The various features of the invention having 15 been described, and ascertained, what is considered to be new and desired to have protected by Letters Patent will be pointed out in the appended claims.

What I claim is:

1. In a telephone system, a plurality of 20 branch exchanges, a main exchange, a plurality of trunks at each branch exchange having trunk indicating equipment associated therewith, means for making any one of said trunk lines busy, means operated 25 when one of said trunks become busy for causing its respective number to be displayed by said trunk indicating equipment, a trunk line extending between each of said branch exchanges and said main exchange, trunk 30 and office indicating equipment associated with the main exchange, means associated with the trunk indicating equipment of the branch exchange for operating the trunk indicating equipment in the main exchange, and means operated in the main exchange 35 for causing said office indicating equipment to be also operated.

2. In a telephone system, a plurality of 40 branch exchanges, a plurality of trunks at each branch exchange having trunk indicating equipment associated therewith, means for making any one of said trunk lines busy, a plurality of relays operable upon a trunk 45 becoming busy for causing the number of the busy trunk to be displayed by said indicating equipment, a trunk line having only four conductors extending from each branch exchange to the main exchange, trunk and office indicating equipment at the latter exchange, means associated with the trunk indicating equipment of the branch exchange for causing the trunk indicating equipment in the main exchange to be operated over 50 a single conductor of the trunk, and means at the main exchange controlled over another conductor of said trunk for causing the operation of said office indicating equipment.

3. In a telephone system, a plurality of 60 branch exchanges, a plurality of trunk lines associated with each branch, trunk indicating equipment at each branch exchange common to the trunks of that branch, means for making any one of said trunks busy, means operable when a trunk becomes busy for causing the number of the busy trunk to be

indicated by said indicating equipment, said means also operable to temporarily disassociate the remaining trunks from said equipment, a main exchange, a trunk line extending from said main exchange to each of said branch exchanges, indicating equipment at said main exchange and means at each of said branch exchanges for controlling said equipment over its associated trunk when the indicating equipment of the branch exchange has been operated.

4. In a telephone system, a plurality of branch exchanges, trunk lines at said exchanges adapted for use by calling subscribers in extending connections, trunk number 80 indicating and supervisory equipment common to said exchanges, common means and means individual to each of said trunks for associating the same with said equipment when taken for use, and means for preventing a second trunk from being associated with said equipment while the first is still associated therewith.

5. In a telephone system, a branch exchange, a main exchange, trunk lines at said branch exchange adapted for use by calling subscribers to extend talking connections, a traffic observing trunk connecting said branch exchange with the main exchange, means for connecting a talking trunk with 90 said traffic trunk when the talking trunk is taken for use, and means at the main exchange for controlling said connecting means over the traffic trunk.

6. In a telephone system, a branch exchange, a main exchange, a trunk line in said branch exchange adapted for use by calling subscribers in extending connections, a trunk connecting said exchanges, means in said branch exchange actuated when the first trunk is seized to connect the first trunk with said last trunk, means at the main exchange operable over said last trunk for informing an observing operator thereat the number of the trunk in use, means controllable by the operator for preventing said trunk being released in case of trouble, signalling means at the branch exchange controllable by the operator to signal an attendant at the branch exchange, means for placing a tone on the connection for informing the operator that the signal is operating, means operable when an attendant responds to stop said signal and tone, and means controllable by the attendant for again starting and stopping said signal and tone at will, to permit the use of said tone to aid in tracing the connection.

7. In a telephone system, a plurality of 125 trunk lines in groups, means for making any of said trunk lines busy, a plurality of trunk indicating lamps, there being one lamp individual to each group and ten lamps common to all groups, means responsive to the seizure of one of said trunks for causing 130

its particular group lamp to glow, and means also responsive to the seizure of said trunk to cause one of the common indicating lamps to glow to indicate the number of the 5 trunk in use in the indicated group.

8. In a telephone system, a plurality of branch offices, a main office, a plurality of trunks at each branch adapted for seizure by calling subscribers thereat, an observation 10 trunk line extending from each branch to the main exchange, means at each branch responsive when a trunk is seized for connecting the seized trunk with the observation trunk extending to the main exchange, and 15 means at the main exchange for informing an operator when the subscriber hangs up his receiver.

9. In a telephone system, a plurality of branch offices, a main office, a plurality of 20 trunks at each branch adapted for seizure by calling subscribers thereat, a trunk line extending from each branch to the main exchange, means at each branch responsive when a trunk is seized for connecting the 25 seized trunk with the trunk extending to the main exchange, and means at the main exchange responsive to such connection for signalling an observing operator.

10. In a telephone system, branch exchanges, a plurality of trunks at each branch, a main exchange, an observation trunk extending from each branch exchange and terminating in said main exchange, means for seizing any of said plurality of 35 trunks, means responsive to the seizure for connecting the seized trunk to the associated observation trunk, and means at the main exchange responsive to such connection for preventing any other seized trunk at any 40 branch from being connected to an observation trunk.

11. In a telephone system, a plurality of branch exchanges, a plurality of trunks adapted for seizure by calling subscribers at 45 each branch, trunk indicating equipment associated with the trunks of each branch, a central exchange, traffic observing trunks extending from each branch to said central exchange, two operator's positions at said central exchange having identical equipment 50 for observing traffic over any of said trunks, and automatic means associated with said equipment for alternately distributing the calls to said positions.

55 12. In a telephone system, a plurality of branch exchanges, a main exchange, trunk lines at each branch adapted for use by calling subscribers in extending connections, trunk indicating equipment at each branch exchange for use by an attendant thereat, a traffic observing trunk line extending from each branch to said main exchange, trunk indicating equipment at the main exchange 60 associated with the trunk indicating equipment of all branch exchanges over said traffic

65 fie observing trunk lines, means at the branch exchanges responsive to the seizure of a trunk for causing the trunk indication to take place at both the main and branch exchanges, an auxiliary operator's 70 traffic observing set for use in locally observing traffic in any one of said branch exchanges, manually operated means for connecting the set with a branch exchange to be observed, and means responsive to such 75 connection for disconnecting said branch from the main exchange observing equipment.

13. In a service observing system, service observing equipment, service observation 80 trunks normally disconnected from said equipment, lines to be observed, means responsive to a call over any one of said lines for connecting the same to an observation trunk and for connecting such trunk to said equipment, and automatic means for preventing any other line from being connected to the same or any other trunk while the first 85 connected line remains connected.

14. In a service observing system, service observing equipment, service observation trunks normally disconnected from said equipment, lines to be observed, means responsive to a call over any one of said lines for connecting the same to an observation 90 trunk and for connecting such trunk to said equipment, and means included in said equipment for rendering said connecting means effective or ineffective at the will of 95 the observing operator.

15. In a service observing system, service observing equipment, service observation trunks normally disconnected from said equipment, lines to be observed, means responsive to a call over any one of said lines for connecting the same to an observation 100 trunk and for connecting such trunk to said equipment, said connecting means being normally inoperative, an operator's head set included in said equipment but normally disconnected therefrom, and means responsive to the connection of said head set with 105 said equipment for rendering said connecting means operative.

16. In a service observing system, service observing equipment located at one exchange, observation trunks extending from said exchange to other exchanges, lines in said other exchanges on which the service is to 110 be observed, means responsive to the taking of one of said lines into use for connecting the same to the observation trunk extending to the exchange in which the line is located, means responsive to such connection 115 for connecting the connected observation trunk to said equipment, and automatic means for preventing any other observation trunk from being connected to said equipment while the first connected trunk remains connected.

17. In a service observing system, service observing equipment located at one exchange, observation trunks extending from said exchange to other exchanges, lines in said 5 other exchanges on which the service is to be observed, means responsive to the taking of one of said lines into use for connecting the same to the observation trunk extending to the exchange in which the line is located, means responsive to such connection for connecting the connected observation trunk to said equipment, and automatic means for preventing any other line in the same exchange from being connected to the 10 observation trunk which is in use. 15
18. In a service observing system, service observing equipment located at one exchange, observation trunks extending from said exchange to other exchanges, lines in said 20 other exchanges on which the service is to be observed, means responsive to the taking of one of said lines into use for connecting the same to the observation trunk extending to the exchange in which the line is located, means responsive to such connection for connecting the connected observation trunk to said equipment, and automatic means for preventing lines in the remainder 25 of said other exchanges from being connected to the observation trunks extending to such exchanges while the first connected line remains connected. 30
19. In a service observing system, service observing equipment, service observation trunks normally disconnected from said 35 equipment, lines to be observed, means responsive to a call over any one of said lines for connecting the same to an observation trunk and for connecting such trunk to said equipment, and means at both ends of the 40 connected trunk for indicating the particular line which is connected thereto. 45
20. In a service observing system, service observing equipment, service observation trunks normally disconnected from said 50 equipment, lines to be observed, means responsive to a call over any one of said lines for connecting the same to an observation trunk and for connecting such trunk to said equipment, means individual to the connected 55 trunk for indicating the particular line which is connected thereto, and additional means common to all said trunks for indicating such line. 60
21. In a service observing system, service observing equipment, service observation trunks normally disconnected from said 65 equipment, lines to be observed, means responsive to a call over any one of said lines for connecting the same to an observation trunk and for connecting such trunk to said equipment, and means common to all said trunks but individual to said equipment for indicating the particular line which is connected 70 to the trunk in use. 75
22. In a service observing system, service observing equipment located at one exchange, observation trunks extending from said exchange to other exchanges, lines in said other exchanges on which the service is to be observed, means responsive to the taking of one of said lines into use for connecting the same to the observation trunk extending to the exchange in which the line is located, means responsive to such connection for connecting the connected observation trunk to said equipment, and means in the 80 said first exchange for indicating the line connected and also the exchange in which such line is located. 85
23. In a service observing system, service observing equipment located at one exchange, observation trunks extending from said exchange to other exchanges, lines in said other exchanges on which the service is to be observed, means responsive to the taking of one of said lines into use for connecting the same to the observation trunk extending to the exchange in which the line is located, means responsive to such connection for connecting the connected observation trunk to said equipment, a line indicating device in the exchange in which the connected line is located, a similar indicating device in the said first exchange, an office indicating device in said first exchange, and means for operating all said devices automatically responsive to the establishment of said connections. 90
24. In combination, a trunk line, lines and means for separately connecting them to said trunk line, an indicator at the originating end of said trunk for indicating in any given case which of said lines is connected to said trunk, a similar indicator at the distant end of said trunk, means for transmitting impulses over the trunk to control the distant indicator, and common apparatus for controlling the first indicator and said impulse transmitting means. 100
25. In combination, a trunk line, lines and means for separately connecting them to said trunk line, an indicator at the originating end of said trunk for indicating in any given case which of said lines is connected to said trunk, a similar indicator at the distant end of said trunk, a switch for controlling the distant indicator, an impulse sender for sending impulses over the trunk to set said switch, and common apparatus for controlling said first indicator and said sender. 115
26. In combination, a trunk line, other lines and means for separately connecting them to said trunk line, relays selectively operated when lines are connected, an indicator controlled by said relays, an impulse sender also controlled by said relays, a switch responsive to impulses transmitted by said sender, and a second indicator controlled by said switch. 125

27. Line indicating apparatus comprising two groups of selectively operable relays, a sending device for transmitting two series of impulses in accordance with the setting of said relays, two switches responsive to said two series of impulses, respectively, and an indicator controlled by said switches. 65
- 5 28. Apparatus for indicating a line designation at two points simultaneously comprising a first set of lamps, conductors for lighting said lamps, a sender device including a point finder having a bank connected to said conductors in multiple with said lamps, a second set of lamps and a second 70 set of conductors, and means controlled by said sender device for lighting said second set of lamps over the second set of conductors. 75
- 10 29. In a service observing system, a central observing station, observation trunks extending from said station to automatic exchanges, each of said automatic exchanges having trunk lines adapted to be seized and released under the control of the subscribers, means responsive to the seizure of a 80 trunk line in one of said exchanges for connecting the trunk line to the observation trunk extending to such exchange, and means controlled from said central station 85 for preventing the subscriber calling from releasing the seized trunk line. 90
- 15 30. In a service observing system, a central observing station, observation trunks extending from said station to automatic exchanges, each of said automatic exchanges having trunk lines adapted to be seized and released under the control of the subscribers, means responsive to the seizure of a trunk 95 line in one of said exchanges for connecting the trunk line to the observation trunk extending to such exchange, and means controlled from said central station for connecting a conductive bridge across the seized trunk line to prevent the calling subscriber from releasing the same. 100
- 20 31. In a service observing system, two exchanges, an observation trunk connecting said exchanges, means for connecting said trunk with a line in one exchange over which a connection is being set up, means under control of an operator at the second exchange for preventing the release of such connection after it is set up, a signal at the first exchange controlled by said operator to notify an attendant at the first exchange that a connection has been locked up, and means for automatically transmitting a signalling current back over the said observation trunk to the operator to notify her that the said first signal is being operated. 105
- 25 32. In a service observing system, an observation trunk, relays for connecting lines to said trunk at one end thereof, said relays being normally inoperative, a common relay 110 for rendering said relays operative, a circuit for said common relay including serially related contacts on all said connecting relays, means for closing said circuit, and means automatically responsive to give an alarm in case one of said serially related contacts is open when the said circuit closing means is actuated. 115
- 30 33. In a multi-office telephone system, an observation set at one office, observation trunks extending from such office to the other offices, means responsive to a call at one of the other offices for connecting the calling line to the observation trunk extending to the office concerned, and means responsive to such connection for connecting the observation trunk to said observation set. 120
- 35 34. In a telephone system, a plurality of branch exchanges, a plurality of trunks at each branch exchange, a main exchange, a trunk line having only four conductors extending from each branch to the main exchange, trunk and office indicating equipment at the main exchange, means at the branch exchange operable when one of said trunks becomes busy for causing the trunk 125 indicating equipment to be operated over a single conductor of the trunk to the main exchange, and means controlled over another conductor of said main exchange trunk for causing the operation of said office indicating equipment. 130
- 40 35. In a telephone system, a plurality of branch exchanges, a plurality of trunks associated with each branch exchange, a main exchange, an observation trunk extending from said main exchange to each of said branch exchanges, means operable when one of said trunks in one of said branch exchange becomes busy for causing the busy trunk to be connected with the observation trunk extending to such branch exchange, said means also operable to temporarily disassociate all the remaining branch exchange trunks from said observation trunks, indicating equipment at said main exchange, and means at each branch exchange for controlling said equipment over its associated observation trunk when a busy branch exchange trunk is connected with its associated observation trunk. 135
- 45 36. In a telephone system, a branch exchange, a main exchange, a trunk line in said branch exchange adapted for use by calling subscribers in extending connections, a trunk connecting said exchanges, means in said branch exchange actuated when the first trunk is seized to connect the first trunk with the said last trunk, means at the main exchange operable over said last trunk for informing an observing operator thereat the number of the trunk in use, means controllable by the operator for preventing said trunk being released in case of trouble, and 140

signalling means at the branch exchange controllable by the observing operator to signal an attendant at the branch exchange.

37. In a telephone system, a plurality of branch exchanges, a main exchange, trunk lines at each branch adapted for use by calling subscribers in extending connections, trunk indicating equipment at each branch exchange, traffic observing trunk lines extending from each branch exchange to said main exchange, trunk indicating equipment at the main exchange common to the trunk indicating equipment of all the branch exchanges by way of said observation trunk lines, and means responsive to the seizure of a trunk for causing the trunk indications to take place at both the main exchange and the branch exchange in which the trunk was seized.

20 38. In a service observing system, service observing equipment, service observation trunks normally disconnected from said equipment, lines to be observed, and means responsive to a call over any one of said lines for connecting the same to an observation trunk and for connecting such trunk to said equipment.

30 39. In a service observing system, service observing equipment, service observation trunks normally disconnected from said equipment, lines to be observed, means responsive to a call over any one of said lines for connecting the same to an observation trunk and for connecting such trunk to said equipment, and means for rendering said last means ineffective in case of a second call if the second call is initiated prior to the disconnection of the said first connected line from the observation trunk.

40 40. In a telephone observation system, a line to be observed, an observation trunk, individual means comprising only two relays for said line for either connecting said line with said trunk or for preventing such connection, a circuit for each of said relays, means for energizing only the first of said relays over its circuit responsive to a call on said line to open the circuit of said second relay and to prevent the connection of said line with said trunk, and means for closing a shunt circuit around said first relay whereby said second relay is energized responsive to a call instead of said first relay thereby connecting said line with said trunk.

45 41. In a telephone observation system, a line to be observed, an observation trunk, individual means comprising only two relays for said line for either connecting said line with said trunk or for preventing such connection, a circuit for each of said relays, means for energizing only the first of said relays over its circuit responsive to a call on said line to open the circuit of said second relay and to prevent the connection of said

line with said trunk, means for closing a shunt circuit around said first relay whereby said second relay is energized responsive to a call instead of said first relay thereby connecting said line with said trunk, and means controlled by the operation of said second relay for removing said shunt circuit.

50 42. In combination, a line to be observed, an observation trunk, and means individual to said line comprising only two relays for either connecting said line with said trunk or for preventing said connection, the first of said relays operative responsive to a call to connect said line with said trunk in case a predetermined condition exists, said second relay operative responsive to a call for preventing the operation of said first relay and the connection of said line with said trunk in case said predetermined condition does not exist.

55 43. In a telephone system, a main exchange, a plurality of branch exchanges, a group of lines in each branch exchange to be observed, an observation trunk extending from each branch exchange to said main exchange, a relay in each branch exchange common to the group of lines therein, and means controlled by an observation operator in said main exchange for energizing the relay in any branch exchange to render the lines of such branch exchange capable of being observed.

60 44. In a telephone system, a main exchange, a plurality of branch exchanges, a group of lines in each branch exchange to be observed, an observation trunk extending from each branch exchange to said main exchange, a relay in each branch exchange common to the group of lines therein, and means controlled by an observation operator in said main exchange for energizing the relay in all said branch exchanges to render all the lines of said branch exchanges capable of being observed.

65 45. In a telephone system, a main exchange, a plurality of branch exchanges, a group of lines in each branch exchange to be observed, an observation trunk extending from each branch exchange to said main exchange, a relay in each branch exchange common to the group of lines therein, means controlled by an observation operator in said main exchange for energizing the relay in all said branch exchanges to render all the lines of said branch exchanges capable of being observed, and means operative responsive to a call on any one of said lines for deenergizing said relays to render the remaining lines in said branch exchanges incapable of being observed.

70 75 80 85 90 95 100 105 110 115 120 125 46. In a telephone system, a main exchange, a plurality of branch exchanges, a group of lines in each branch exchange to be observed, an observation trunk extending

from each branch exchange to said main exchange, a relay in each branch exchange common to the group of lines therein, means controlled by an observation operator in said main exchange for energizing the relay in all said branch exchanges to render all the lines of said branch exchanges capable of being observed, means operative responsive to a call on any one of said lines for seizing the observation trunk extending to the branch exchange in which said call originates, and means operative responsive to said seizure for deenergizing said relays to render the remaining lines in said branch exchanges incapable of being observed.

47. In a telephone system, a main exchange, a plurality of branch exchanges, a group of lines in each branch exchange to be observed, an observation trunk extending from each branch exchange to said main exchange, a relay in each branch exchange common to the group of lines therein, means controlled by an observation operator in said main exchange for energizing the relay in all said branch exchanges to render all the lines of said branch exchanges capable of being observed, a relay in said main exchange individual to each of said observation trunks, means operative responsive to a call on any one of said lines for seizing the observation trunk extending to the branch exchange in which said call originated, means operative responsive to said seizure for deenergizing the relay associated with said seized trunk, the individual relay in said main exchange also energized responsive to said seizure, and means operative responsive to the energization of said individual relay for deenergizing the said relays in the other branch exchanges to render the lines therein incapable of being observed.

48. In a telephone system, a main exchange, a plurality of branch exchanges, a group of lines in each branch exchange to be observed, an observation trunk extending from each branch exchange to said main exchange, a relay in each branch exchange common to the group of lines therein, means controlled by an observation operator in said main exchange for energizing the relay in all said branch exchanges to render all the lines of said branch exchanges capable of being observed, and means responsive to a call on any one of said lines in said branch exchanges for deenergizing said relays excepting the relay in the branch exchange in which the call originated to render the remaining lines incapable of being observed, said means also completing a holding circuit for maintaining said relay energized.

49. In a telephone system, a main exchange, a plurality of branch exchanges, a

group of lines in each branch exchange to be observed, an observation trunk extending from each branch exchange to said main exchange, a relay in each branch exchange common to the group of lines therein, means controlled by an observation operator in said main exchange for energizing the relay in all said branch exchanges to render all the lines of said branch exchanges capable of being observed, means responsive to a call on any one of said lines in said branch exchanges for deenergizing said relays excepting the relay in the branch exchange in which the call originated to render the remaining lines incapable of being observed, said means also completing a holding circuit for maintaining said relay energized, and means controlled by an observation operator for releasing said relay.

50. In a telephone service observation system, a main exchange, a branch exchange, an observation trunk extending between said exchanges, groups of lines at said branch exchange adapted to be observed, a relay in said branch exchange controlled over said trunk for rendering said lines capable of being observed, means at said main exchange for energizing said relay, a step-by-step switch at said branch exchange, means responsive to a call on one of said lines for connecting such line to said trunk and for operating said switch to indicate the number of the calling line, means at said main exchange for deenergizing said relay, and means controlled by said switch for preventing the reenergization of said relay until said switch has been returned to normal position.

51. In a telephone system, a switch having three wipers, means for operating said switch, a relay in said switch for controlling the transmission of impulses, means for energizing said relay over a circuit including the first of said wipers, means controlled by said relay for closing a locking circuit for itself including the second of said wipers, and means for deenergizing said relay comprising a circuit including said third wiper.

52. A stepping mechanism for an automatic switch comprising a motor magnet, a stepping relay, circuits for said magnet and relay and means for closing them, a shunt circuit around said relay to prevent its energization, means controlled by said magnet for opening said shunt circuit, and means controlled by said relay for opening said magnet circuit.

In witness whereof, I hereunto subscribe my name this 17th day of November, A. D., 1922.

JOHN E. OSTLINE
